UNITED STATES PATENT OFFICE.

CARL F. BRAUN, OF SAN FRANCISCO, CALIFORNIA.

THREE-WAY BY-PASS VALVE.

Application filed January 15, 1919. Serial No. 271,277.

To all whom it may concern:

Be it known that I, CARL F. BRAUN, a citizen of the United States, residing at San Francisco, in the county of San Francisco and State of California, have invented new and useful Improvements in Three-Way By-Pass Valves, of which the following is a specification.

This invention relates to a by-pass valve, 10 and particularly to a three-way globe valve of the by-pass type.

It is the principal object of the present invention to provide a by-pass valve controlling the flow of fluid into and out of 15 the runs of a pipe line and to a side line, all of which pipe lines are in a single plane and the valve stem disposed in a plane at right angles thereto, thus permitting a compact valve to be constructed and placed in 20 inaccessible locations without making the operation of the valve difficult.

The invention further consists of the parts and the construction, combination and arrangement of parts as hereinafter more fully described and claimed, having reference 25 to the accompanying drawings in which—

Fig. 1 is a vertical central section through the valve.

Fig. 2 is a similar section taken at right 30 angles to Fig. 1.

Fig. 3 is a section similar to Fig. 1, showing a modification of the valve.

Fig. 4 is a vertical central section taken 35 at right angles to Fig. 3.

Fig. 5 is a view in horizontal section illustrating another form of the valve shown in Figs. 1 and 2.

Referring to the drawings in detail, A indicates the main casing of the valve which 40 in this instance is divided into three separate chambers indicated at 2, 3 and 4, by means of a pair of horizontal interspaced partition walls 5 and 6. These walls form the central chamber 2 and the upper and 45 lower chambers indicated at 3 and 4 respectively. Communicating with the lower and upper chambers are a pair of flanged pipe connections 7 and 8 and communicating with the central chamber is a flanged pipe 50 connection 9. The several pipe connections are all mounted on the same plane and

means have been provided for distributing and regulating a flow of fluid or liquid through the valve so that it may be distributed through one or two of the pipe lines 55 connecting with the valve, as the operator may desire. That is, liquid entering through the connection 9 may be by-passed through either the connections 7 or 8 or through both, or liquid entering through either of the connections 7 or 8 may be distributed through both of the other connections.

This is accomplished in the following manner: secured on top of the casing is a 60 head member 10 on which is formed a stuffing box 11. Extending through the stuffing box is a valve stem 12, on the upper end of which is secured a handle 13 and suitably attached to the lower end of the 65 stem is a double-faced valve 14 which is adapted to be moved into engagement with one or the other of a pair of valve seats, shown at 15 and 16. These seats are formed in bushings 17, which have been screwed 70 into the body of the valve to permit the seats to be removed for re-grinding or replacement. This feature does, of course, not form any part of the present invention as 75 it is a common expedient resorted to in different forms of valves.

The stem 12 supporting the valve is preferably guided by a lower extension 18 which passes through a guide lug 19 formed in the lower part of the valve casing. The upper 80 end of the stem is threaded, as at 20 and as it passes through a threaded block 21, supported by standards 22, it can readily be seen that the valve 14 may be raised or lowered to close one or another of the openings 23 and 24 formed in the valve seat bushings 17.

The operation of the valve is as follows: With the valve positioned, as shown in Fig. 1, it can readily be seen that if the liquid 90 enters through the connection 8 in the direction of arrow A, that the liquid thus entering will pass through the upper chamber 3, the passage 23, the central chamber 2, and will then finally discharge through the 95 connection 9; similarly, if the valve 14 is partly opened or moved to a central position

between the valve seats 15 and 16, that it will be possible to by-pass a portion of the flow through the connection 7. Again, if liquid should enter the connection 9, it 5 would be possible to direct the entire flow through the connection 8 or to partly open the valve 14 and divert the flow through both the connections 7 and 8 or to move the valve into engagement with the valve seat 10 15 and direct the entire flow through the connection 7, any of the operations being possible, whether the inflow takes place through one connection or the other.

By referring to Figs. 1 and 2, it will be 15 seen that the central chamber 2 is in direct alignment with the connection 9 and that the connections 7 and 8 are mounted in alignment with each other. A direct flow is thus secured to the central chamber 2 from 20 the connection 9 while distribution of the liquid through the connections 7 or 8 takes place through the valve seat openings 23 and 24. By referring to the modified form of the valve shown in Figs. 3 and 4, it will 25 be seen that this construction is partly reversed. The valve there shown is also provided with three chambers; that is, the central chamber 2^a, and an upper and a lower chamber, as indicated at 3^a and 4^a respectively. The central chamber is in this instance directly connected with the connection 8, the lower chamber communicates with the connection 7 and the upper chamber with the right angular connection 9. A 30 direct flow may thus be obtained through the connection 8 and distribution or bypassing will take place through the right-angular connections 7 and 9. Construction of the valve is otherwise similar to the valve 35 shown in Figs. 1 and 2, the only difference being that the connection 8 communicates directly with the central chamber, as shown in Figs. 3 and 4, while the connection 9 communicates with the central chamber in the 40 preferred form of the structure shown in Figs. 1 and 2.

The form of the device disclosed in Fig. 5 embodies aligned inlet and outlet passages 50 7 and 8, disposed at angles to the passageway 9 and an aligned passageway 9', all of said passageways being in the same plane and controlled by the valve mechanism as previously described. The communication between the passageways 7, 8 55 and 9 is identical with that shown in Figs. 1 and 2 of the drawings. However, there is uninterrupted communication between the passageways 8 and 9'. This provides a valve in which simultaneous communication may 60 be established between the passageways 7, 8, 9 and 9', or between passageways 7 and 9 and separate communication between passageways 8 and 9', or again, between the passageways 8 and 9 and separate communication 65 between the passageways 8 and 9', thus

making it possible to have a constant flow of fluid through pipes disposed at an angle to each other and providing means for allowing these pipes to simultaneously communicate with the other passageways.

In reviewing the various operations of the structures shown in the drawings, it will be noted that the valve illustrated in Figs. 1 and 2 may be actuated to establish communication between passageways 7 and 9, 8 and 9, or all three passageways 7, 8 and 9. In the form of the valve shown in Figs. 3 and 4, communication may be established between the passageways 7 and 8, 7, 8 and 9, or the 70 75 passageways 8 and 9.

The valve construction as here shown is particularly adapted as a by-pass valve where several pipe lines approach each other on the same plane, and particularly where it would be practically impossible to install 80 the valve if elbows, uprights or vertical connections were required. The present valve permits the several pipe lines connected with the valve, to enter the same on a common plane. This is of considerable importance 85 as it permits installation where other valves could not possibly be employed, and it furthermore reduces the number of nipples and elbows and the friction losses otherwise occurring with ordinary valves.

Having thus described my invention, what I claim and desire to secure by Letters Patent is—

1. A distributing valve adapted to control the intercommunicating flow between a plurality of pipes lying in the same plane, comprising a casing formed with a plurality of outlet and inlet openings disposed in a common plane, a central valve chamber directly connecting with only one of said openings, by-pass chambers communicating with and disposed upon opposite sides of the central chamber, each chamber having an outlet or inlet opening, valve seats in opposite walls of the central chamber and through which communication between the central and by-pass chambers may be established, and a valve member adapted to be moved to positively seat upon either of said valve seats, the actuating stem of said valve member being disposed at right angles to the plane of the valve seats and the plane of the casing openings.

2. A distributing valve adapted to control the intercommunicating flow between a plurality of pipes lying in the same plane, comprising a casing formed with a plurality of outlet and inlet openings disposed in a common plane, a central valve chamber directly connecting with only one of said openings, by-pass chambers connecting with opposite sides of the central chamber, each chamber having one or more outlet or inlet openings, valve seats formed in opposite walls of the central chamber and through which com- 120 125 130

munication with the by-pass chambers is established, and a valve member adapted to be moved to positively seat upon either of said valve seats, the actuating stem of said valve member being disposed at right angles to the plane of the valve seats and the plane of the casing openings.

In testimony whereof I have hereunto set my hand in the presence of two subscribing witnesses.

CARL F. BRAUN.
